HENRY H. GOVE, OF BIDDEFORD, MAINE; CHARLOTTE M. GOVE, ADMINISTRATRIX OF SAID HENRY H. GOVE, DECEASED, ASSIGNOR OF ONE-HALF TO HOWARD R. WHITEHEAD, OF SACO, MAINE.

WEFT-CUTTING MECHANISM FOR LOOMS.

Application filed March 20, 1917. Serial No. 156,174.

To all whom it may concern:

Be it known that I, HENRY H. GOVE, a citizen of the United States, residing at Biddeford, in the county of York and State 5 of Maine, have invented certain Improvements in Weft-Cutting Mechanisms for Looms, of which the following description, in connection with the accompanying drawings, is a specification, like reference characters on the drawings indicating like parts in the several figures.

This invention relates to weft-cutting mechanisms for automatic looms, that is, looms in which the weft in the working shuttle is automatically replenished just before it otherwise would become exhausted. In the looms of this type now on the market, it is usual to employ two cutting or parting mechanisms at the weft-replenishing side of 10 the loom. One of these mechanisms usually is supported by the temple and is positioned close to the selvage edge of the cloth while the other is located close to the shuttle-box. It is necessary of course to cut two threads 15 at each weft-replenishing operation, namely, the weft carried by the spent bobbin which is ejected from the shuttle by the bobbin-changing or weft-replenishing mechanism and the weft end of the new bobbin that is 20 inserted in the shuttle by said mechanism. Usually the temple cutter is operated continuously, while the other cutter is operated only during the relatively brief period in which the weft-replenishing operation is being 25 effected, provision being made for bringing the weft thread within the range of operation of the temple cutter only when it is desired to have the thread severed. It is 30 obvious that this arrangement is relatively complicated and that the wear on the temple cutter is extremely rapid. With these considerations in view, it is the general object 35 of the present invention to devise a weft-cutting mechanism which will be simple in construction, reliable in operation and will be 40 so organized and arranged that it will not be subject to rapid wear or deterioration.

To this end the invention comprises, in its preferred form, a single cutter located close 45 to the selvage of the cloth at the weft-replenishing side of the loom and operating mechanism therefor arranged to actuate the cutter only during the relatively brief inter-

val necessary to enable it to cut the end portions of the weft carried by both the spent 55 and the full bobbins.

The invention will be readily understood from the following description reference being made to the accompanying drawings in which:

Fig. 1 is a plan view showing only those parts of an automatic loom necessary to an understanding of this invention;

Fig. 2 is a vertical cross sectional view taken substantially on the plane indicated 65 by the line 2-2, Fig. 1;

Fig. 3 is a plan view on a relatively large scale showing the more important parts of the cutting mechanism;

Fig. 4 is a vertical cross sectional view 70 through the mechanism shown in Fig. 3; and

Figs. 5 and 6 are rear elevations of a part of the mechanism shown in Fig. 3 showing the relative positions of the parts.

In the drawings 2 indicates the lay, 4 the shuttle-box at the weft-replenishing side of the loom, 6 the shuttle, 8 the breast beam and 10 the temple. All these parts are arranged in the usual way, the construction shown being that of the Northrop 80 loom which is widely used in the trade. In this type of loom the weft-replenishing mechanism comprises a feeler mechanism in combination with a bobbin-changing mechanism so arranged as to be brought into operation by the action of the feeler mechanism.

A rock shaft 12 connects these two mechanisms, and the arrangement is such that when the feeler mechanism detects the fact that the weft on the bobbin in the working shuttle is nearly exhausted, it rocks the shaft 12 and brings the bobbin-changing mechanism into operation, which acts automatically to eject the spent bobbin from the shuttle and replaces it with a full bobbin. All this mechanism is so well known to those skilled in this art, that any further description of this mechanism or any illustration of it is unnecessary for the purpose of clearly disclosing the present invention. 100

It is obvious that when the spent bobbin is ejected from the shuttle 6 the weft or filling thread is still attached to the cloth and extends from the selvage of the cloth to the shuttle-box 4. It is, of course, necessary 105 to sever this thread preferably, close to the

selvage of the cloth. When the full bobbin has been inserted in the shuttle and the shuttle has made its first pick, the end portion of this new filling thread extends from 5 the point on the hopper or magazine at which it is fastened to the selvage of the goods, and this thread also must be severed. It is, therefore, necessary merely to have the weft-cutting mechanism operate twice at each weft-replenishing operation, once to cut the weft end of the old or spent bobbin, and the other 10 to sever the end portion of the thread carried by the new or full bobbin. The mechanism herein described for the purpose of 15 clearly disclosing this invention is arranged to operate automatically upon the initiation of the weft-replenishing action to make the two cuts required for this purpose and then to stop automatically.

20 This mechanism comprises a cutter supported on the temple 10 and consisting of a stationary blade 14, secured fast to the temple, and a movable blade 16 pivoted to the blade 14 so that the two blades form a 25 pair of shears. These blades normally are held in their open position by means of a spring 18. The blades 14 and 16, when they are open, lie just behind the apex of the shed so that there is no danger of their cutting or chafing the filling or weft during 30 the normal operation of the machine.

The cutter is operated by an actuating device 20 which is slidably mounted on the lay and has a part shaped to engage a 35 downwardly curved arm or tail piece 22 which is adjustably secured to the movable blade 16 of the cutter by a screw and slot connection, indicated at 24 (Fig. 4). As clearly shown in Fig. 3, the part 20 is 40 notched, as indicated at 25, so that when this notch is opposite the tail piece 22 of the shears the actuator cannot operate the shears.

Since it is desired to have the cutter or 45 shears work at certain times only during the operation of the machine, a mechanism is provided which maintains the actuator 20 normally out of its co-operative relationship to the shears. The actuator is shown 50 in this position in Fig. 3. This mechanism comprises a block 26, to the upper side of which the actuator 20 is rigidly secured; a rod 27 on which the block 26 is fixed and which is arranged to slide longitudinally 55 through bearings 28 and 28' fastened to a plate 29 that is secured to the front face of the lay 2; and a spring 30 which encircles the rod 27 and bears at one end against the bearing 28, (Fig. 3) and at its opposite end 60 against a collar 31 fast on the rod 27. Another collar 32, adjustably secured to said rod, is arranged to engage the bearing member 28' and limit the movement of the rod 27 and the block 26 under the influence of 65 the spring 30. It is obvious that since the

rod 27, block 26 and actuator 20 all move together, the spring 30 holds these parts normally in such a position that the notch 25 of the actuator is opposite the tail piece 22 of the shears, and therefore maintains the 70 actuator normally in its inoperative relationship to the shears. Since all of these parts are secured to the lay, they will be swung backward and forward, toward and from the temple, by the movement of the 75 lay.

As above stated, the weft-cutting mechanism is controlled by the action of the weft-replenishing mechanism. For this purpose a rock shaft 12, which as above stated, 80 is normally stationary, but is rocked in a counter-clockwise direction (see Fig. 2) in order to throw the bobbin-changing mechanism into operation, has fixed to it an arm 35, the forward end of which is bent or 85 deflected to the right, as shown in Figs. 2 and 3. A lever 36, pivoted to the right hand end of the rod 27 and fulcrumed on a stud 37 carried by a bracket 38 which is secured to the bottom of the lay 2, as shown 90 in Fig. 2, normally lies above the arm 35. But, when this arm is swung upwardly by the rocking movement of the shaft 12, as above described, the bent forward end of the arm is brought into a position beside 95 and close to the path of movement of the lower end of the lever 36. This rocking movement of the shaft 12 and arm 35 takes place when the lay is at the forward part 100 of its stroke and consequently, when the lay swings back, the contact of the lever 36 with the bent end of the arm 35 will rock the lever about its fulcrum 37 in such a direction as to force the rod 27 toward the left, as shown in Fig. 3.

This movement carries the actuator 20 into its operative relationship to the cutter and a pawl and ratchet mechanism is provided to retain the actuator in this position temporarily. Referring to Figs. 4, 5, 110 and 6, it will be seen that the block 26 is slotted to receive a plunger 40 which is recessed to receive a pawl 41 and a spring 42 that holds the pawl in a depressed position where it engages the teeth of a ratchet 115 or rack 44 that is secured to the plate 29. The teeth on the ratchet 44 are staggered, as clearly shown in Figs. 5 and 6, the teeth A and C lying at the front side of the rack 44 and the teeth B and D at the rear side; 120 and the plunger 40 is mounted to slide transversely of the ratchet 44 to carry the pawl 41 into engagement with either line of teeth. Normally this plunger is held in its forward position by means of a spring 125 46 (see Fig. 4) and in this position the head 48 of the plunger projects in front of the block 26. The temple 10 carries an arm having a depending portion 50 through which the temple is actuated, and which 130

normally is out of alignment with the head 48 of the plunger 40, as shown in Fig. 3; but the movement of the block 26 toward the left, as above described, brings the head 5 48 into alignment with the arm 50 so that the first forward stroke of the lay, after the shifting movement of the block 26, causes the head 48 to strike the part 50 and thus move the plunger 40 inwardly. Provision, of course, is made for adjusting the 10 mechanism for different widths of cloth. It is for this purpose that the slots are formed in the rack 44 and the additional holes are made in the plate 29, as shown in Figs. 5 15 and 6.

It will now be understood that the parts are normally in the relative positions in which they appear in Fig. 3, the lay 2, at this time being at the forward part of the 20 stroke and the actuator 20 being in its inactive or inoperative relationship to the cutter. While the parts remain in this position, therefore, the cutter is maintained in its inoperative or inactive condition by the 25 spring 18. As soon, however, as the action of the weft-replenishing mechanism is initiated, the arm 35 is rocked and the block 26 and the actuator 20 are shifted toward the left (Fig. 3), in the manner above described, where they are held temporarily by the pawl 41 engaging the farthest tooth A (Fig. 5) of the rack 44. This shifting movement of the parts takes place upon the first backward stroke of the lay after the 35 shaft 12 has been rocked. When the lay swings forward again, the wide part 20 of the actuator strikes the inclined portion of the tail piece 22 and operates the shears, thus causing them to cut the weft thread 40 of the spent bobbin in the shuttle which, in the meantime, has been shot through the shed into the shuttle-box 4 in readiness to have its bobbin changed.

While the lay is at the forward part of 45 its stroke the bobbin in the shuttle is changed and when the lay swings back again the shuttle makes its first pick after receiving the new bobbin. When the lay beats up this pick the actuator 20 strikes 50 the tail piece 22 a second time and thus gives to the cutter its second actuation causing it to sever the new bobbin thread close to the selvage of the cloth.

When the lay makes its first forward 55 stroke after the shifting of the actuator into its operative position, the head 48 of the plunger 40 strikes the stationary arm 50 in about the position indicated in Fig. 5. The arm 50 thus pushes the plunger 40 inwardly 60 toward the lay and moves the pawl 41 out of engagement with the tooth A and behind the tooth B. The tooth B is slightly in advance of the tooth A and the spring 30 thus operates at this time to force the block 26 65 and the parts carried by it forward until

the pawl 41 strikes the tooth B. As soon as the lay 2 swings back away from the arm 50, the spring 46 pushes the plunger 40 forward and moves the pawl 41 back into alignment again with the tooth A, but at a point 70 in front of the tooth A and immediately behind the tooth C. This allows the spring 30 to push the block 26 ahead a short distance until the pawl 41 strikes the tooth C. The pawl and ratchet mechanism then maintains the parts in this position, as shown in Fig. 6, until the next forward stroke of the lay, when the operation just described is repeated by the second contact of the plunger head 48 with the stationary arm 75 50. That is, the plunger 40 is pushed over until the pawl is behind the tooth D and the spring 30 pushes the block 26 ahead until the pawl strikes this tooth. The second cutting movement of the shears takes place at this time, and when the lay swings backward again, the spring 46 slides the plunger 40 to the left, thus moving the pawl 41 laterally out of engagement with the tooth D, whereupon the spring 30 slides the 80 block 26 and the parts carried thereby toward the right (Fig. 3) until the collar 32 strikes the bearing member 28'. This movement carries the actuator into its inoperative relationship to the cutter and it is 85 thereafter maintained in this position until the next weft-replenishing operation is initiated.

It will thus be seen that the initiation of the operation of the weft-replenishing mechanism brings into operation means that shift the actuator into its operative relationship to the cutter and that thereafter the actuator is returned to its normal or inoperative position again by an automatic mechanism which operates step by step and which allows the actuator to operate the cutter only a predetermined number of times. The cutting mechanism and the operating parts therefor are at rest at all times except 100 during the relatively short period immediately after the action of the weft-replenishing mechanism has been initiated, and consequently, the mechanism is subject to very little wear. It will also be evident that the mechanism is entirely automatic in its action, that its movements are, for the most part, positively effected and that it operates 105 with absolute certainty. By using a weft-cutting mechanism of this character, it is not necessary to use the second cutter which usually is employed and is located close to the shuttle-box.

While the cutter has herein been shown as mounted on the temple, it is obvious that 115 it may be mounted independently of the temple if desired, and it will also be understood that the invention may be modified in many forms differing in arrangement and in details of construction from the embodiment.

ment herein shown and described without departing from the spirit or scope of this invention.

What is claimed as new, is:—

- 5 1. In a weft replenishing loom, the combination of a lay, a weft cutter, a normally stationary support for said cutter, an actuator for said cutter carried by the lay, a spring operative to hold said actuator normally in an inoperative position with reference to said cutter, means controlled by the weft replenishing mechanism for shifting said actuator into its operative relationship to the cutter, and additional 10 means for retaining said actuator temporarily in said operative position while it operates the cutter a plurality of times and then allowing said spring to return the actuator again to its inoperative position.
- 15 2. In a weft-replenishing loom, the combination of a lay, a weft cutter supported on a stationary part of the machine, an actuator for said cutter carried by the lay and normally held in an inoperative position with reference to the cutter, means controlled by the weft-replenishing mechanism for shifting said actuator longitudinally of the lay into its operative relationship to the cutter, and means for automatically returning said actuator to its inoperative position again after it has operated the cutter 20 a predetermined number of times.
- 25 3. In a weft-replenishing loom, the combination of a lay, a weft cutter, an actuator for said cutter carried by the lay, a spring acting on said actuator to hold it normally in an inoperative position with reference to the cutter, means controlled by the weft-replenishing mechanism for shifting said actuator into its operative relationship to the cutter, a pawl and ratchet mechanism arranged to retain the actuator 30 temporarily in said operative position, said ratchet having staggered teeth, and means operated by the motion of the lay for moving the pawl into engagement with the successive teeth of said ratchet to enable said spring to return said actuator step by step to its inoperative position.
- 35 4. In a weft-replenishing loom, the combination with a lay, of a weft-cutter, an actuating device for said cutter carried by the lay, a spring acting on said device to hold it normally in an inoperative position with reference to said cutter, mechanism controlled by the weft-replenishing means for moving said device into its operative position against the tension of said spring, a pawl and ratchet mechanism arranged to retain said device in its operative position, 40 and means for releasing said pawl and ratchet mechanism at predetermined times to enable said spring to return said actuator step by step to its inoperative position.
- 45 5. In a weft-replenishing loom, the combination of a lay, a weft cutter, an actuator for said cutter carried by the lay, a spring operative to hold said actuator normally in an inoperative relationship to said cutter, means controlled by the weft replenishing mechanism for shifting said actuator into its operative relationship to said cutter, and means comprising a ratchet and pawl mechanism for retaining said actuator temporarily in said operative position but arranged to be released automatically after the cutter has been operated a predetermined number of times to allow said spring to return the actuator again to its inoperative position.
- 50 6. In testimony whereof I have signed my name to this specification.

HENRY H. GOVE.
